UNITED STATES PATENT OFFICE

135,026

DESIGN FOR A POWDER BELLOWS

Mortimer H. Hirschfield, Great Neck, N. Y., assignors to Tone Laboratories, Inc., New York, N. Y., a corporation of New York

Application December 5, 1942, Serial No. 108,952

Term of patent 7 years

To all whom it may concern:

Be it known that I, Mortimer H. Hirschfield, a citizen of the United States of America and residing in Great Neck, Nassau County, Long Island, New York, have invented a new, original, and ornamental Design for a Powder Bellows, of which the following is a specification, reference being had to the accompanying drawing, forming part thereof.

The figure is a perspective view of a powder bellows showing my new design.

I claim:

The ornamental design for a powder bellows, as shown.

MORTIMER H. HIRSCHFIELD.
